(57) **CLAIM**(51) **LOC (7) Cl. 13-03**

I claim the ornamental design for a light emitting diode, as shown and described.

(52) **U.S. Cl. D13/180**

DESCRIPTION

(58) **Field of Search** D10/104, 114;

FIG. 1 is a perspective view of the light emitting diode showing my new design;

D13/180, 182; D26/37; 174/52.2; 257/79,

FIG. 2 is a top plan view of the light emitting diode according to FIG. 1;

88, 89, 93–96, 91, 98, 99, 100, 432, 433,

FIG. 3 is a left side elevational view of the light emitting diode according to FIG. 1;

434, 678, 684, 698; 313/499, 500; 362/35,

FIG. 4 is a front elevational view of the light emitting diode according to FIG. 1;

226, 249, 287, 294, 800

FIG. 5 is a right side elevational view of the light emitting diode according to FIG. 1;

(56) **References Cited**

FIG. 6 is a bottom plan of the light emitting diode according to FIG. 1; and,

U.S. PATENT DOCUMENTS

FIG. 7 is a rear elevational view of the light emitting diode according to FIG. 1.

The broken line showing of the environment is for illustrative purpose only and forms no part of the claimed design.
